UNITED STATES PATENT OFFICE.

WILLIAM H. RIDGWAY, OF COATESVILLE, PENNSYLVANIA.

STEAM HYDRAULIC HOIST.

No. 838,632.

Specification of Letters Patent.

Patented Oct. 16, 1906.

Application filed September 30, 1904. Serial No. 228,690.

To all whom it may concern:

Be it known that I, WILLIAM H. RIDGWAY, a citizen of the United States, and a resident of Coatesville, Pennsylvania, have invented 5 certain Improvements in Steam Hydraulic Hoists, of which the following is a specification.

My invention relates to elevators or hoists of the steam hydraulic type—that is to say, 10 those in which the piston or plunger of the hoisting-cylinder is acted upon by water or other liquid which is contained in a vessel or tank to which steam or other fluid under pressure is admitted in order to raise the cage 15 or platform of the elevator and from which said steam or other fluid is exhausted in order to permit said cage or platform to descend. Hereinafter for convenience I shall allude to the fluid under pressure as "steam."

20 The objects of my invention are to prevent the sudden or abrupt starting of the movement of the hoist in its ascent, to counterbalance or partially counterbalance the weight of the hoist, to permit free escape of 25 the steam from the pressure-tank when the exhaust is open, to maintain at all times a full supply of water or other liquid in the pressure-tank, and to permit of the proper overflow of water from said tank without 30 loss of steam.

In the accompanying drawings, Figure 1 is a view, partly in side elevation and partly in section, of a platform-hoist, illustrating the application of my invention thereto. 35 Fig. 2 is a vertical section, on an enlarged scale, of the pressure-tank, valve-chest, and valve-operating mechanism. Fig. 3 is a plan view, partly in section, of said valve-chest and valve-operating mechanism. Fig. 4 is 40 a sectional plan view of the steam-spreader with which the pressure-tank is provided. Fig. 5 is an enlarged section of said steam-spreader, and Fig. 6 is a vertical section of a combined drainage and check valve with 45 which the pressure-tank is provided.

Referring first to Fig. 1 of the drawings, 1 represents the platform of a hoist which is mounted upon a piston-rod or plunger 2 and is adapted to move vertically between guides 50 3, the piston-rod or plunger being adapted to a cylinder 4 and being caused to rise when liquid under pressure is admitted to the said cylinder and permitted to descend when said liquid is exhausted from the cylinder. It 55 should be understood, however, that my invention is not limited to a direct-acting hoist

of the character described, but is applicable as well to elevators in which the movement of the piston or plunger in the cylinder is transmitted to the cage or platform through the 60 medium of intervening ropes and pulleys. In fact, the character of the hoisting mechanism forms no essential part of my invention, the latter relating to the construction of the pressure-tank, its valves and valve mechanism, and to the location of said tank in respect to the cylinder of the hoisting mechanism. 65

The pressure-tank is shown at 5 and is located at a higher level than the cylinder 4, 70 being connected to said cylinder by a pipe 6, so that a hydrostatic column is provided, said column having sufficient head to counterbalance, or partially counterbalance, the weight of the platform 1 and plunger 2 or 75 other hoisting devices which may be employed in connection with the cylinder.

The pipe 6 is preferably furnished with a stop-valve 7, connected to a controlling-rope 7a, so that it can be operated independently 80 of the valve mechanism described hereinafter.

The pressure-tank 5 is when the hoist-platform is at its lowest point intended to be filled with water or other liquid up to the 85 level of an overflow-pipe 9, and in order to preserve a proper supply of liquid in the tank at all times such liquid in limited volume is constantly fed to the tank 5 through a suitably-valved pipe 10, the surplus liquid passing off through the overflow-pipe 9, which is provided with a valve resembling an ordinary check-valve used in an inverted position, such valve being shown in Fig. 6, on reference to which it will be observed that the 90 valve has a casing 11, with partition 12, on the under side of which is formed a seat for a spherical valve 13, the latter being normally supported in a position slightly below this seat by means of a rest carried by a suitable bottom cap 14. A valve constructed in this manner will permit of a slow flow of the overflow-water or other liquid through the same in the direction of the arrows shown in Fig. 6; but a quicker rush of steam or other fluid 105 through the overflow-pipe 9 will effect the lifting of the valve 13, so as to close the same against its seat and arrest the further flow of the steam.

A suitable vent-pipe 15 provides for the escape of any steam which may pass before the closing of the valve. 110

The upper portion of the pressure-tank 5 communicates, through a pipe 16, with a steam-chest 17, which has three chambers 18, 19, and 20, the chamber 18 being the live-steam chamber, the chamber 19 constituting a steam-distributing chamber, and the chamber 20 an exhaust-chamber, said chambers 19 and 20 being in communication with each other through an opening 21 in the central partition, as shown in Fig. 3, which opening can be opened or closed by movement of a valve 22, contained in the exhaust-chamber 20, and operated in the manner hereinafter described.

15 The end of the pipe 16 which projects into the pressure-tank 5 is provided with a steam-spreader 23, which consists of a hollow circular disk having around its periphery tangentially-disposed outlets 24, said spreader also having in its top openings 25, which are normally closed by internal valves 26, the latter being self-closing, but free to open when the pressure outside of the spreader is greater than the pressure inside of the same.

20 25 In the partition between the chambers 18 and 19 of the valve-chest is an opening forming a seat for a valve 27, the latter having a rod which passes through a stuffing-box on the top of the valve-chest and is connected to 30 a lever 28, hung at one end to a link 29 on the valve-chest and provided at its opposite end with a depending pawl 30, which is normally held in the position shown in Fig. 2 by a spring 31, but can yield in the direction of the arrow against the pressure of the said spring when sufficient force is exerted to thus move it.

35 The pawl 30 is acted upon by the teeth of a ratchet-wheel 32, which is secured to a shaft 33, having a sheave 34, around which passes the governing rope or chain 8, said shaft also having an eccentric 35, whose rod 37 is connected to the rod 38 of the valve 22, as shown in Fig. 3. The movement of the valve 22 is in excess of the width of the port or passage 40 45 21, and the ratchet-wheel 32 has a blank portion 36, corresponding to that portion of the movement of the valve which is actually devoted to opening and closing said part.

If the hoisting-platform is lowered, the 50 valve 27 closed, the passage 21 closed by the valve 22, the water in the tank 5 at the level of the overflow-pipe, and the space in the tank above the level of the water filled with air, manipulation of the controlling rope or chain 55 60 8 so as to cause forward movement of the shaft 33 and wheel 32 will effect a number of successive openings and closings of the valve 27, depending upon the extent of the forward movement of the ratchet-wheel, and 65 consequently upon the number of teeth of the same which act upon the pawl 30, the live steam under pressure therefore passing in a series of successive impulses from the chamber 18 of the valve-chest into the distributing-chamber 19 and thence into the spreader 23,

by which it is discharged in the form of tangential jets into the upper portion of the pressure-tank 5, the water or other liquid being thereby forced from said tank into the cylinder 4, so as to raise the hoist, as shown in Figs. 1 and 2.

70 By admitting steam into the distributing-chamber 19 of the valve-chest in a series of successive impulses in the manner described a gradually-increasing pressure is exerted 75 upon the water or other liquid in the pressure-tank, and the plunger in the cylinder 4 is started slowly and gradually attains its maximum speed, thereby preventing the sudden or abrupt start which is likely to result if the full volume of steam under pressure is at once admitted to the pressure-tank.

75 The steam discharged by the spreader into the upper portion of the pressure-tank retains its position therein, a body of air intervening 80 between the steam and the surface of the water, which body of air acts as a non-conductor and serves to prevent the relatively rapid condensation of steam, which would take place if the steam came in direct contact with the water.

85 When it is desired to permit the descent of the hoist, the governing rope or chain 8 is moved in a direction the opposite of that before described, which has the effect of turning 90 the eccentric 35 so as to move the valve 22 rearwardly in the exhaust-chamber 20 of the valve-chest, thereby uncovering the passage 21 and opening the upper end of the pressure-tank to the exhaust, the backward movement 95 of the ratchet-wheel 32 during the earlier part of said movement causing its successive teeth to trip the pawl 30 and the blank portion 36 of the ratchet-wheel being finally brought under the pawl, so that there is no 100 movement of the valve-lever 28 during such backward movement of the ratchet-wheel.

105 When the ratchet-wheel 32 is again turned forwardly, there is, owing to the blank portion 36 of said wheel, no operation of the lever 28 and valve 27 until the valve 22 has been moved forwardly to an extent sufficient to close the exhaust.

110 The steam escapes from the upper portion of the pressure-tank 5 through the openings 115 24 of the spreader 23 and also through the valved openings 25 of the same, the latter increasing the area of escape as compared with the area of inlet, so that the steam can be quickly exhausted from the pressure-tank.

115 Having thus described my invention, I claim and desire to secure by Letters Patent—

1. The combination of the hoisting-cylinder, the liquid-containing tank communicating therewith and means for admitting steam to said tank by a succession of impulses, substantially as specified.
2. The combination of a hoisting-cylinder,

- a liquid - containing tank communicating therewith, valves for admitting steam to and exhausting it from said tank, means for actuating said valves including a pawl and ratchet 5 for the steam-valve, said ratchet having a blank portion whereby opening of said valve is prevented until after the exhaust-valve has been closed, and an overflow-pipe for the tank, substantially as specified.
- 10 3. The combination of the hoisting-cylinder, the liquid-containing tank communicating therewith, a steam-chest having a valve for governing the flow of steam from said chest into the tank, a lever connected to said 15 valve and means for vibrating said lever so as to alternately open and close the valve and admit steam to the tank in a succession of impulses, substantially as specified.
4. The combination of the hoisting-cylinder, the liquid-containing tank communicating therewith, a steam-chest, a valve controlling the flow of steam from said chest into the tank, and means for operating said valve, said means comprising a toothed wheel and a 25 transmitting device having a pawl acted upon by said wheel, said pawl being free to move in one direction but held against movement in the opposite direction, substantially as specified.
- 30 5. The combination of the hoisting-cylinder, the liquid-containing tank communicating therewith, a steam-chest having a valve for controlling flow of steam into the tank and another valve for controlling the exhaust 35 of steam from the tank, a valve-operating shaft, and means whereby a movement of said shaft in one direction causes it to operate the inlet-valve so as to admit steam in a succession of impulses while movement of 40 the shaft in the opposite direction causes it to operate the exhaust-valve, substantially as specified.
6. The combination in a hoisting apparatus, of a hoisting-cylinder, a liquid-containing 45 tank communicating therewith, valves for controlling the inlet of steam to and its exhaust from said tank, and means for operating said valves, said means including an eccentric connected to one valve and a multi- 50 lated ratchet operative upon the other valve, the ratchet having an inactive portion placed

to prevent opening of its valve until after the eccentric has been sufficiently moved to close its valve, substantially as specified.

7. The combination of the hoisting-cylinder, 55 the liquid-containing tank communicating therewith, the steam-chest having a live-steam chamber and a distributing-chamber, a valve governing the flow from one chamber to the other, mechanism including a pawl 60 and ratchet for operating said valve and a communication between the distributing-chamber and the tank, substantially as specified.

8. The combination of the hoisting-cylinder, 65 the liquid-containing tank communicating therewith, a valve-chest having a live-steam chamber, a distributing-chamber, and an exhaust-chamber, a communication between said distributing-chamber and the 70 tank, a valved communication between the live-steam chamber and the distributing-chamber, and a valved communication between the distributing-chamber and the exhaust-chamber, with ratchet mechanism for 75 causing steam to be admitted in a series of impulses, substantially as specified.

9. The combination of the hoisting-cylinder, 80 and the liquid-containing tank communicating therewith, with a steam-supply pipe and a spreader contained in the tank and consisting of a hollow disk with tangential exit-openings in its peripheral portion, and provided with exhaust-valves, substantially 85 as specified.

10. The combination of the hoisting-cylinder, 90 the liquid-containing tank communicating therewith, a combined steam inlet and outlet pipe communicating with the tank and a spreader connected to said pipe and having openings through which the steam flows both in entering and leaving the tank, and valved openings through which the steam flows only in leaving the tank, substantially as specified. 95

In testimony whereof I have signed my name to this specification in the presence of two subscribing witnesses.

W.M. H. RIDGWAY.
